Inventor

Casper W. Miles.

UNITED STATES PATENT OFFICE.

CASPER W. MILES, OF ANDERSON TOWNSHIP, HAMILTON COUNTY, OHIO:

FLOOR-SURFACER.

No. 870,836.

Specification of Letters Patent.

Patented Nov. 12, 1907.

Application filed March 25, 1907. Serial No. 364,470.

To all whom it may concern:

Be it known that I, CASPER W. MILES, a citizen of the United States, residing in Anderson township, in the county of Hamilton and State of Ohio, have invented 5 certain new and useful Improvements in Floor-Surfacers, of which the following is a specification.

My invention relates to improvements in mechanism for surfacing floors and similar operations.

One of its objects is to provide an improved portable 10 tool which can be manipulated to secure true and even surfaces on floors.

Another object is to provide a rotary cutter for such tool, which will automatically drive dirt and cuttings away from the tool.

15 Another object is to provide a simple and efficient arrangement of parts which will permit an accurate adjustment for the depth of cut, and prevent excessive cutting.

Another object is to provide improved means for adjusting the tool to and from the work.

Another object is to provide an improved adjustable and detachable tool guard.

Another object is to provide means for regulating the depth of cut, starting and stopping the cutter and guiding the tool from a standing position.

It further consists in certain details of form, combination, and arrangement, all of which will be more fully set forth in the description of the accompanying drawings, in which:

30 Figure 1 is a perspective view of my improved tool. Fig. 2 is a diagram section on line $v-v$ of Fig. 1 of the form of mechanism for securing the vertical adjustment of the tool. Fig. 3 is an end elevation of one of the rotary tools or cutters. Fig. 4 is a view similar to Fig. 2, 35 showing a modification thereof. Fig. 5 is a side elevation of the tool and adjusting mechanism, showing a modification. Figs. 6, 7, and 8 are detail perspective views of the adjusting mechanism of Fig. 5. Fig. 9 is a detail perspective view of a handle by which the tool 40 may be operated from a standing position, and showing means for stopping and starting the motor and adjusting the depth of cut. Fig. 10 is a perspective view of a modified form of base plate. Fig. 11 is a detail view of a rotary scraping or finishing tool. Fig. 12 is a side elevation of a tool for applying sand paper to the work.

In the accompanying drawings, A, represents the base which rests upon the work and serves to gage the depth of cut and prevent the tool from cutting irregularly or unevenly. As shown in Fig. 1, the base consists of a metal plate having a plane surface next to the work, and is intended to slide over the work. This plate may terminate as shown in Fig. 1, at one side of the cutter, or as indicated in Fig. 5 may have fingers, a, at opposite edges, projecting on opposite sides of the 55 cutter.

B, represents an electric motor; the shaft, C, of the

armature being journaled at opposite ends in bearings in the heads, b, b'.

D, represents the rotary tool which is secured to the end of the armature shaft, outside the head, b. For 60 rough work, I employ a cutter head armed with knives, d, which shave or cut away the projecting or uneven parts of the work. The arms, d', are shaped so as to create an air current when rotating, which current blows away the cuttings and grains of sand and dirt, 65 leaving a clean surface for the plate, A, to travel over, and assisting to keep the knives sharp. After an even surface has been attained, or where the grain of the wood is such that the cutter of Fig. 3, cannot be used to advantage, I employ a tool, D', having arms similar 70 to Fig. 3, but with blades, d'', set to scrape instead of cut, the surface. By the use of the scraping tool, a smoother and more even surface may be attained. If desired, the surface may be finally polished by the use of tool, D'', the periphery of which is armed with a strip 75 of sand paper, d'''.

In order to protect the user against accidental injury, I provide a guard, E, over the rotary cutter and in order to permit the tools to be readily removed and replaced, I hinge the guard at e, by means of a rod, or pin, 80 to the head, and lock it in position at e', by means of a rod, or pin, or other suitable latch mechanism. Thus, by unlatching the guard at e', it may be turned up out of the way, or by removing the hinge-rod, the guard may be detached.

85 The motor, B, is hinged at one side to plate, A, on a line parallel with the axis of the armature shaft. On the opposite side, as shown in Figs. 1 and 2, I provide adjusting screw, F, journaled to the motor, B, and engaging a threaded sleeve, f, which is hinged to the plate, A, at f'.

f'' represents a pointer, to indicate on a scale, f''', on sleeve f the depth of cut which will be taken by the knives or scrapers. As shown in Figs. 5 to 8, the adjustment is effected by means of an eccentric, G, which is 95 pivotally attached to the motor.

g, represents a link hinged to plate, A, at one end, and fitting over the eccentric, G, at the opposite end.

g', represents a collar seating on the rectangular shoulder, g'', of the eccentric, G, to hold the link in place. A 100 handle, g'', serves to turn the collar, g', and eccentric, G, on their pivot, and a spring actuated pin, g'', enters one of the holes, g'', in the link, to lock the parts to the adjusted position.

In Fig. 10 I have shown a modification, A', in the base plate, in which the plate consists of an open frame, in which are journaled a series of rollers, h, so that the lower face of the plate is slightly lifted from the work and normally rides upon the rollers, but so that the plate is ever ready to rest upon the work and prevent too deep a cut should the rollers run into depressions in the work.

In operating the tool, Fig. 1, the operator gets down close to the work, and by means of handles, I, guides the tool wherever required, being able to stop and start the motor by means of switch lever, *et al.* Where the operator desires to operate the tool from a standing position, 5 I provide a long hand-bar, K, at the upper end of which are handles, *k*, *k'*, which enable the operator to guide the tool wherever desired. The handle, *k*, is split and provided with a switch lever, *l*, which springs open 10 automatically to stop the motor when released, and which is closed to start the motor by grasping the handle. As shown in Fig. 4, a rod, *m*, is journaled to the underside of bar, K, which rod carries a beveled gear in mesh with a beveled gear, *m'*, on the screw rod, F, to 15 vary the depth of cut. Where the eccentric, G, is employed, the handle, *g*, and its spring pin, are mounted at the upper end of a rod, M', Fig. 9 and the opposite end of rod, M', is connected by a link, *n*, with a stud, *n'*, on the collar, *g'*. 20 The mechanism herein specified is capable of considerable modification, without departing from the principle of my invention.

Having described my invention, what I claim is:

1. In a mechanism of the character indicated, a plate 25 adapted to rest against the face of the work, an electric motor hinged thereto on a line parallel with the axis of the armature shaft, a rotary tool carried by said armature shaft, and means for adjusting said motor on said hinge relative to said plate.
2. In a mechanism of the character indicated, an electric 30 motor, a rotary cutter-head having fan-shaped arms to drive dirt and obstructions from the path of the knives, a plate to contact with the work, and adjusting mechanism adapted to adjust said plate to and from the axis of said cutter.
3. In a mechanism of the character indicated, an electric 35 motor, a rotary tool mounted upon the armature shaft of said motor, said tool being so shaped as to create an

air current to blow the cuttings and dirt from the path of the knives, an open-work guard embracing said tool, 40 said guard being hinged to one side of the motor frame and locked to said frame at its opposite side, a plate to contact with the work and mechanism for adjusting said plate to and from the axis of rotation.

4. In a mechanism of the character indicated, an electric 45 motor, a rotary tool mounted on the armature shaft of said motor, a plate contacting with the work, mechanism to adjust said plate to and from the axis of said armature shaft, a handle-bar connected at one end of said motor and provided with handles at its opposite or free end, and 50 means located near the free end of said handle-bar to actuate said adjusting mechanism.

5. In a mechanism of the character indicated, a plate 55 adapted to rest against the face of the work, a motor frame hinged to said plate, a rotary tool mounted upon an axle parallel with said hinge, and actuated by said motor, means for adjusting said motor on said hinge relative to said plate.

6. In a mechanism of the character indicated, a plate 60 adapted to rest against the face of the work, a motor carried by and adjustable to and from said plate, and a rotary cutter carried and driven by said motor.

7. In an article of the character indicated, a plate comprising a frame and a series of rollers journaled thereto, said rollers to contact with the work and normally hold the plate slightly away from the work, a motor carried by said plate and adjustable relative thereto, and a rotary cutter carried and driven by said motor.

8. In a mechanism of the character indicated a plate 70 adapted to contact with the work, a motor carried by said plate, a rotary tool driven by said motor and carried by and adjustable relative to said plate, a handle-bar adapted to guide said tool from a standing position and carrying at its free end mechanism for shifting said tool.

In testimony whereof I have affixed my signature in 75 presence of two witnesses.

CASPER W. MILES.
